UNITED STATES PATENT OFFICE

167,294

DISH OR SIMILAR ARTICLE

Howard S. Andrews, Oneida, N. Y., assignor to Oneida, Ltd., Oneida, N. Y., a corporation of
New York

Application August 20, 1951, Serial No. 16,386

Term of patent 14 years

(Cl. D44—15)

To all whom it may concern:

Be it known that I, Howard S. Andrews, a citizen of the United States, residing at Oneida, county of Madison, and State of New York, have invented a new, original, and ornamental Design for a Dish or Similar Article, of which the following is a specification, reference being had to the accompanying drawing, forming a part thereof, in which:

Figures 3 and 4 are sectional views on the respective lines 2—2 and 4—4 of Figure 1, also on an enlarged scale.

The essential feature of the design is the embossed motif repeated around the border of the dish.

I claim:

The ornamental design for a dish or similar article, substantially as shown and described.

HOWARD S. ANDREWS.
